AUTOMATIC RADIO STATION SELECTOR

William Rice and Maurice H. Goldberg, Chicago,
Ill.; said Goldberg assignor to said Rice

Application June 24, 1933, Serial No. 677,416

3 Claims. (CL 250—20)

This invention relates generally to radio receiving apparatus, and more particularly to selective control mechanism for the same.

There have been a number of proposals, in the past, to provide a mechanism for automatically tuning radio receiving circuits at timed intervals, but such mechanism have not proved satisfactory for various reasons. The objections to devices of this type in the past have been that they all relied upon the variable radio condenser for varying the stations selected thereby, the mechanism devised being merely some means for moving said radio condenser to a predetermined point at a predetermined time.

This means not only made for a somewhat complicated and expensive mechanism, but also failed to accurately tune in the selected station as anyone familiar with radio receiving apparatus know how impossible it is to properly tune in a desired radio circuit by merely moving the condenser thereof to a predetermined fixed position. As a consequence, none of these prior devices proved commercially practical.

The present invention is a distinct departure from the prior art proposals in that it combines simple adjustable tuning elements which may be set at predetermined values with simple means for selectively tuning in predetermined broadcasting stations at predetermined time intervals by the mere movement of simple mechanism, such, for example, as a simple switch or the like.

It is, therefore, one of the main objects of this invention to provide an improved mechanism which may be selectively set manually, whereby automatically various stations may be tuned in periodically and the radio instrument set into operation.

Another object of this invention is to provide a mechanism of the above mentioned type having tuning means selectively responsive to simple switching mechanism associated therewith.

A further object of this invention is to provide a mechanism of the above mentioned type in which simple switching mechanism are employed for selectively tuning in predetermined broadcasting stations and automatic time control means for actuating said switching mechanism.

A still further object of this invention is to provide a plurality of tuning elements for selectively tuning in predetermined radio receiving circuits by the movement of simple mechanism and time controlled means associated therewith for periodically changing from one to the other of

said tuning elements, whereby different stations may be periodically selected thereby.

A still further object of this invention is to provide time controlled means for controlling the actuation of switching mechanism which are associated with radio tuning elements to bring the latter into service for selectively tuning in predetermined broadcasting stations.

A still further object of this invention is to provide in combination with a radio receiving circuit including a plurality of tuning elements which are selectively responsive to simple switching mechanism, time controlled means operable to selectively actuate said switching mechanism, whereby the receiving circuit will be tuned to a predetermined station, and to periodically change the switching mechanism after a predetermined interval of time and to break the supply of power to the circuit at a predetermined time.

A still further object of this invention is to provide a mechanism of the character described applicable to radio receivers as at present commonly used, whereby the variable condenser of such radio receivers may be readily thrown out of service and supplemented by other tuning means selectively responsive to simple switching mechanism, which mechanism may be selectively and individually set to function to automatically tune in various stations at timed intervals.

A still further object of this invention is to provide a device of the above mentioned character which embodies not only manually and selectively set means for automatically tuning a radio receiver to bring in various broadcasting stations at predetermined desired times, but which also automatically stops or cuts off from operation the receiver subsequent to the completion of certain predetermined programs, the automatically stop means being also manually and selectively set for such operation, said automatic tuning means being independent of the usual variable tuning elements at present commonly used on radio receivers.

A still further object of this invention is to provide a mechanism of the character described which will be simple in construction, assembly and operation, which may be produced along lines convenient for low cost manufacture and which will be highly efficient for carrying out the purposes for which it is designed.

With the foregoing and other objects in view, which will appear as the description proceeds, the invention consists in certain novel features of construction, arrangement and combinations

of parts hereinafter more fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of our invention, we have illustrated in the accompanying drawings a preferred embodiment thereof, from an inspection of which when considered in connection with the following description, our invention, its mode of construction, assembly and operation, and many of its advantages should be readily understood and appreciated.

Referring to the drawings in which the same characters of reference are employed to indicate corresponding or similar parts throughout the several figures of the drawings:

Figure 1 is a front elevational view of a panel board with mechanism embodying the present invention supported thereby;

Fig. 2 is a bottom plan view of the mechanism shown in Fig. 1;

Fig. 3 is a bottom plan view of the selector drum;

Fig. 4 is an enlarged fragmentary view of the opposite side of the drum shown in Fig. 3, parts thereof being broken away to show the inside construction thereof;

Fig. 5 is a view in elevation of one of the selector elements;

Fig. 6 is a view taken on line 6—6 of Fig. 5 showing the selector element in one of its operative positions;

Figs. 7, 8, 9, 10, and 11 are views similar to Fig. 6, but showing the selector element in the other of its operative positions;

Fig. 12 is an elevational view partly in section showing the manual means for actuating the selector elements; and

Fig. 13 is a diagrammatic view of the electric circuit employed.

Stated generally, the invention involves the provision of a plurality of simple adjustable tuning elements, the values of which may be set to bring in predetermined broadcasting stations, said tuning elements being capable of being brought into operation by the closing of a simple switching mechanism. These adjustable tuning elements are provided in addition to the variable tuning units as at present commonly used in radio receivers.

For the purpose of automatically actuating said switching mechanism, there is provided a time controlled mechanism, including a plurality of selector elements, each of which is adapted to be moved to a plurality of adjusted positions, said positions being arranged so as to bring about either one of a plurality of desired operations. When in one position each of said selector elements is capable of completely turning off the radio receiver, when in another position it will permit the tuning of the radio receiver by the usual turning units, and when in its other position it will automatically close the switch mechanism to tune the receiver to predetermined broadcasting stations.

Referring to the drawings more specifically by characters of reference, the number 10 designates a panel mounted in a radio receiver upon which our improved mechanism may be conveniently supported. Thus as shown in Fig. 1,

carried by said panel are a plurality of simple adjustable condensers 11, 12, 13, and 14 which are controlled by the switches 17, 18, 19, and 20, respectively. The said switches may be of any suitable and well known construction, and, as illustrated in the drawings, are carried in blocks 21 which are secured to the bracket 22, said bracket also supporting intermediate its ends suitable bus bars 23 which are connected in circuit with the condensers 11 to 14. Thus the simple movement of the switching elements 17 to 20 will close the circuit through predetermined sets of the adjustable condensers 11 to 14. Suitable conductors 24 connect the condensers 11 to 14 with their co-operating switching elements 17 to 20.

In order to actuate said switching elements automatically and also at timed intervals the following improved mechanism is provided. Mounted on the panel 10 for rotary movement thereon is a selector drum, generally designated by the reference character 25, said drum being formed of a pair of disks 26 and 27 rigidly secured to each other in spaced relation in any suitable manner. Adjacent the outer periphery of the drum are mounted a plurality of selector elements 28, there being forty-eight of such elements equally spaced apart to permit for the predetermined setting of the device for a complete twenty-four hour period at half hour intervals.

Each of the selector elements 28 is provided with a circular portion 29 adjacent one end thereof which is received in a suitable opening provided therefor in the disk 26 and a reduced circular portion 30 provided at its opposite end for reception in an opening provided therefor in the other disk 27. These portions 29 and 30 thus form suitable bearings for the selector elements 28, whereby the same may be rotated relative to said drum. Intermediate the portions 29 and 30 the selector elements are of a hexagonal cross section as shown in the drawings, and are provided with a plurality of transverse grooves 31, said grooves being arranged in offset relation and there being a total of six of said grooves in each of said selector elements. Thus by rotating the selector elements in a manner to be hereinafter more fully described, the desired groove 31 of any selector element may be brought to any one of the six positions shown in Figs. 6 to 11.

Each of the selector elements is provided with a specially shaped head 32 which is shown to be triangular, said head being adapted for reception in a similarly shaped socket for imparting the desired rotary movement to the selector elements 28. In order to keep the said selector elements in the desired adjusted positions to which they may be moved, there is provided a flat annular spring 33, shown in Fig. 4, said spring normally pressing against the inner sides of said elements for holding the same in the positions to which they may have been moved. The resiliency of the spring 33, however, permits the ready turning of said elements when actuated by the actuating member to be presently more fully described.

The selector drum 25 is mounted for rotary movement in a vertical plane, as shown in Fig. 1, and for that purpose it is disposed on a suitable sleeve 34 carried by the panel 10. Intermittent half hour rotary movement is imparted to the selector drum by means of a pawl 35 carried on the outer end of a lever 36, said lever being pivoted intermediate its ends to the sleeve 34 and has its opposite end disposed in position to be actuated by a double acting cam 37 which is con-

nected with a suitable clock mechanism 38 supported on the panel by means of the bracket 39, said cam 37 being connected with the block mechanism so as to make one full revolution every hour. The clock 38 may be of any suitable construction and may be either spring wound or electrically driven. If an electric clock is used the same may be of the well known synchronous motor type and may be included in the circuit, as shown in Fig. 13, so that the same may be in constant operation as long as the house current to which it is connected is uninterrupted.

The pawl 35 is adapted to co-operate with suitable ratchet teeth 40 provided on the disk 27 of the selector drum. A spring 41 normally urges said pawl into engagement with said ratchet teeth. If desired, the ratchet teeth 40 may be eliminated and the pawl 35 arranged to operate with the projections 38 of the selector elements 28, which projections, it will be noted, extend a substantial distance beyond the outer surface of the disk 27, as more clearly shown in Fig. 5 of the drawings.

As shown in Fig. 1, one arm of the lever 45 is disposed in the path of movement of the cam 37 while the other arm thereof is yieldably urged in a clockwise direction by means of the coil spring 42, which spring will also be effective for holding the lever in contact with the cam 37. From the above it should be apparent that the cam 37, because of its rotary movement imparted to it by the clock 38, will actuate the lever 45 to move the same in a counter clockwise direction against the action of the spring 42.

When the lever has passed the highest point on the cam 37, the spring 42 will move the lever and pawl to rotate the selector drum 25 in a clockwise direction through an angle equal to the angle between any two selector elements 28 or one-forty-eighth of a revolution. A stop member 43 is provided for preventing greater movement than that of the selector drum. The selector drum 25 will thus be advanced a predetermined distance every half hour, this movement being entirely automatic and controlled by the clock mechanism 38.

As already explained, each of the selector elements 28 is adapted for disposition in either one of six positions to which it may be moved. In order to move a desired selector element to a predetermined position, we have provided the following improved mechanism. A lever 45 having a pointer 46 provided at one end is pivotally mounted intermediate its ends on a shaft 47, which shaft is adapted to be received in the sleeve 34 for rotation therein.

On one face of the selector drum are provided suitable designations indicated by the reference character 48, said designations designating the selector elements by numbers from 1 A. M. to 12 noon, and from 1 P. M. to 12 midnight. The pointer 46 is so mounted as to co-operate with said numbers, whereby the disposition of the pointer opposite a designated time number will permit the setting of the desired selector element to the desired position for that particular time interval.

The end of the lever 45 disposed opposite that of the pointer is provided with an enlarged portion 49 in which is slidably mounted a shaft 50 to the bottom end of which is secured a socket 51 adapted for receiving the triangular shaped head 52 of the selector elements 28. A suitable disk 52 is secured to the upper face of the enlarged por-

tion 49 in any suitable manner, such, for example, as by means of the screws 53.

Disposed above the disk 52 and in spaced relation thereto is a hand dial 54, said dial being rigidly keyed to the upper end of the shaft 50 for imparting rotary movement thereto. A coil spring 55 is interposed between the disk 52 and dial 54, said spring surrounding said shaft and normally holding the latter in its uppermost position, as shown in Fig. 12. A suitable shoulder 56 is provided on the shaft 50 intermediate its ends for limiting its upward movement. A cut-out 57 is provided on the periphery of the dial 54 through which cut-out may be observed certain designations 52' provided on the disk 52 for facilitating in the setting of the selector elements to the desired positions.

As shown more clearly in Fig. 2, the normal position of the socket 51 will be out of engagement with the selector drum 45. However, when it is desired to set the selector drum so as to bring in a certain broadcasting station at a predetermined time, the lever arm 45 is moved to a position where the pointer 46 thereof will be disposed opposite the designated time. The shaft 50 may then be depressed to bring the socket 51 into engagement with the head of the selector element disposed directly below it.

The hand dial 54 may then be rotated to bring the said selector element to the desired position, said position being indicated by the markings or designations on the disk 52. As there are only six positions to which any selector element may be moved, the markings on the disk 52 will, therefore, be from 1 to 6. By thus observing the markings of the disk 52 through the cut-out 57 of the hand dial, the particular selector element being actuated may be moved to the desired position as noted by the indication on the disk 52.

In order to lock the drum 25 against movement when the selector elements are being set by the hand dial 54, there is provided a suitable braking mechanism which, in the embodiment illustrated, comprises a lever 58 pivoted at one end to the panel 10, as shown at 59, and having its opposite end disposed in position to engage the selector drum 25 when moved to such position by an arm 60, which arm is disposed against the underside of the lever 58 and is adapted when moved about its pivot 59 to urge said lever 58 against the drum, and when moved in the opposite direction to permit the lever 58 to move out of engagement with said drum. A flat spring 62 having one end thereof secured to the panel 10 is provided for co-operating with the arm 60 for holding the latter 58 in either of two adjusted positions. A stop member 63 may be provided for limiting the movement of the arm 60 in one direction.

As hereinbefore mentioned the selector elements are employed for actuating the switching elements 17 to 20 at predetermined time intervals to bring about the desired operation of the device during that time interval. Those disposed directly below the selector drum 25 are a plurality of levers 65, 66, 67, 68, 69, and 70, said levers 65 being pivoted intermediate their ends on a stud 71, which stud is secured to the panel 10 as shown at 72 in Fig. 1. The said levers 65 to 70 are mounted so that their longest and heavier ends are on the right of their pivot 71, as viewed in Fig. 70 1, whereby they will by their own weight be urged in a clockwise direction at all times.

Each of the levers 65 to 69 is provided adjacent the end disposed opposite the drum 25 with a projecting portion 73, which portion is adapted to be

received in the groove 31 of the selector element disposed directly above it when said element is in a position where one of the grooves 31 thereof is in alignment with the edge of the lever, as shown in full lines in Fig. 6 of the drawings. The rear portions of the levers 65 to 70 are arranged in the proper spaced positions with their projecting portions 73 disposed against the lowermost selector element in the drum 28. When in that position it will be readily apparent that one of said levers will have its projection 73 disposed in the groove 31 of said lowermost selector element.

The opposite ends of the lever 65 to 69 are disposed in position against the switching elements 17 to 20 and are provided with upstanding toes 74, which toes are adapted to engage their co-operating switching elements for moving the same out of contacting engagement with the bus bars 23.

20 The lever 70 is provided adjacent one end with a depending portion 75, which portion is adapted to engage the movable contact 76 of a switch 16-77, the other contact 77 of which is fixed. The switch 16-77 is in the main line connecting the 110 volt house current with the radio receiver. The contact 76 is so arranged that when the depending portion 75 is in a down position, that is, when its portion 73 is out of engagement with the groove 31 of the selector element disposed directly above it, the circuit to the radio receiver will be closed and the receiver capable of operation. However, when the projection 73 of the lever 70 is disposed in the groove 31 of the selector element directly above it, it will permit the opening of the switch 16-77, thus cutting off the power to the radio receiver and shutting off the same. The lever 70, therefore, is employed for the purpose of maintaining the circuit to the receiver closed when the selector element directly above it is in any one of its five positions of the six positions to which it may be moved and to break said circuit when said selector element is in its last of its said six positions.

One of the other levers 65 to 69, say, for example, the lever 69, is arranged so that when its projecting portion 73 is in the groove 31 of the selector element and directly above it, it will permit the actuation of a switch element 78, to cut in the usual tuning elements 79 and 80, whereby the radio receiver may be tuned in the ordinary manner. When in this position it will be apparent that the other switches 11 to 20 will be open by reason of their engagement by their respective levers 65 to 68, thus cutting out from the circuit the simple adjustable condensers 11 to 14, thereby permitting the ordinary operation of the receiver for tuning the same in the usual manner to bring in desired broadcasting stations by actuating the variable condensers 79 and 80. It will also be noted that at this time the switch 16-77 will be in a closed position, thereby closing the circuit to the radio receiver.

When one of the other levers 65 to 68 are disposed in a position with the projection 73 thereof disposed in the groove 31 of the selector element directly above it, one of the switch elements 17 to 20, which is disposed opposite the toe 74 of that particular lever, will be permitted to make contact with the bus bars 23, thus completing the circuit through the respective adjustable condensers 11 to 14, thereby bringing in a particular station to which the particular condenser has been previously tuned.

From the above it will be readily apparent that each of the selector elements may be set in one

of six positions for co-operating with one of the levers 65 to 70 for bringing about a desired operation of the radio receiver. Thus when in one position it will permit the swinging of the lever 70 to bring about the opening of the switch 16-77 for completely shutting off the radio receiver.

When in another position it will permit the swinging of the lever 69 to permit the actuation of the switch 78 for cutting out the condensers 11 to 14 and for cutting in the variable condensers 79 and 80 for permitting the usual operation of the radio receiver. When in one of the remaining four positions the selector element will co-operate with one of the remaining levers to permit the closing of the circuit automatically through one of the condensers 11 to 14, thus bringing in a particular broadcasting station for which the particular condenser has been previously set.

In the use of our invention the simple adjustable condensers 11 to 14 are set in the desired positions to correspond to the station that the particular condenser is to tune in, that is to say, the condenser 11 may be set to tune in station WBBM, the condenser 12 to tune in station WGN, the condenser 13 to tune in station KYW and the condenser 14 to tune in station WMAQ. Although four such adjustable condensers are illustrated in the drawings, it is understood that a lesser or greater number of said simple adjustable condensers may be employed with equally satisfactory results. Thus the selector elements may be octagon in cross section, thereby permitting its disposition in eight instead of six different positions, in which case a plurality of six semi-fixed condensers may be employed for bringing in automatically six broadcasting stations by the mere closing of simple switching mechanism.

The condensers 11 to 14 may be of any type suitable for this purpose, and in the preferred embodiment, these may be of what is known as the semi-fixed type and are characterized by the fact that the value of the condenser may be adjusted in a very simple manner, such, for example, as by the simple manipulation of a screw or the like.

The operation of the device should be readily apparent from the above without further description. As already stated, the purpose of the device is to manually set the same for a complete twenty-four hour period and then to permit it to automatically operate the receiver either to tune in certain desired broadcasting stations or to shut off the receiver or to place the receiver in condition to permit its ordinary operation, all of this being accomplished without further attention until the order is to be changed.

As an example of the operation of the device, assuming the pointer 46 to be in the position shown in Fig. 1, in which position it will be noted it is disposed opposite the selector element between the times as indicated on the drum 12 noon and 1 P. M. or 12:30 P. M. With the pointer in this position the actuation of the hand dial 84 to move the selector element disposed directly below it will set this selector element to the desired position for the half hour interval beginning with 12:30 P. M. The position to which the particular selector element is to be moved may be observed on the disk 52 by noting the numbers 52' thereon. Thus as shown in Fig. 1, the designation on the disk 52, visible through the cut-out in the hand dial, is the number 1, which number 7

may correspond to the position of the selector element shown in full lines in Fig. 6.

Now assuming that when in that position the groove 31 of said selector element which will be exposed for reception therein of the projection 13 of the lever 65, which lever will then be permitted to swing about its pivot for releasing the switch element 17 to close a circuit to the semi-fixed condenser 11 for bringing in broadcasting station WBBM. When, therefore, the time of 12:30 P. M. has arrived the particular selector element will be disposed at the lowermost point of the selector drum and will be in the position to permit the swinging of the lever 65 about its pivot to bring about the closing of a circuit through the condenser 11 and at that time station WBBM will be heard from.

This particular station will be tuned in for the entire half hour period at the end of which a further rotary movement will be made by the selector drum bringing into operative position the next successive selector element which will be effective for permitting the swinging of one of the levers 66 to 70 to bring about the desired operation of the receiver for the next half hour period. Particular attention is directed to the fact that the device is capable of not only tuning in automatically desired broadcasting stations, but also of completely shutting off the receiver at predetermined times and for predetermined periods of time.

From the foregoing it will readily be seen that the present invention provides a novel and improved structure which may readily accomplish the various objects for which it has been designed. It will be understood that the invention is not confined to the specific structural details herein shown and described, and that numerous changes and modifications and the further use of equivalents of the present invention may be resorted to without departing from the spirit or scope of the invention as outlined in the appended claims.

Having now described our invention in the manner in which the same operates, what we claim and desire to secure by Letters Patent is:

1. In a device for automatically conditioning a radio receiving set to receive radio waves from selected broadcasting stations, said receiving set having a plurality of semi-fixed tuning elements, switching mechanism to which said tuning elements are selectively responsive, a rotatable selector drum having a plurality of equally spaced circumferentially disposed selector elements for selectively actuating said switching mechanism, means for intermittently rotating said drum to

bring each selector element to a stationary position at the same point and to retain said drum in said stationary position for a predetermined time interval, means provided on each of said selector elements including a plurality of cam surfaces 5 for co-operation with the actuating means for said switch mechanism whereby said selector elements may be set to bring about the desired operation of a predetermined part of said switching mechanism to bring in a predetermined broad- 10 casting station.

2. In combination with a radio receiving set having a plurality of semi-fixed tuning elements, switching mechanism to which said tuning elements are selectively responsive, means for selectively actuating said switching mechanism to successively select different impulses to be received, said last mentioned means including an intermittently rotating drum upon the periphery of which are provided a plurality of equally spaced selector elements each of said selector elements being provided with a plurality of cam surfaces arranged on the periphery thereof in offset relation to each other, each of said cam surfaces being arranged for co-operation with said switching mechanism to bring in a predetermined broadcasting station, means for rotating said drum to bring each selector element to a stationary position and to retain the same in said position for a predetermined time interval, and means for actuating each of said selector elements to bring the desired cam surfaces thereof into operative position with relation to the switching mechanism.

3. In combination with a radio receiving set, a plurality of tuning elements provided therefor, simple switching mechanism to which said tuning elements are responsive, means actuating said switching mechanism, said last mentioned means including a rotatable drum, time controlled means for intermittently rotating said drum, selector elements circumferentially disposed upon the periphery of said drum, said selector elements being mounted for rotary movement relative to said drum, each of said selector elements being provided with a plurality of cam surfaces arranged in offset relation to each other, and means for actuating said selector elements to bring the desired cam surface thereon into operative position, whereby said selector elements may be set to bring about the desired operation of a predetermined part of said switching mechanism to bring in a predetermined broadcasting station.
